UNITED STATES PATENT OFFICE.

POSEY W. BETTINGER, OF SAN JOSE, CALIFORNIA.

VALVE-SPRING LIFTER.

1,246,528.

Specification of Letters Patent. Patented Nov. 13, 1917.

Application filed March 14, 1917. Serial No. 154 717

To all whom it may concern:

Be it known that I, POSEY W. BETTINGER, a citizen of the United States, residing at San Jose, in the county of Santa Clara and State of California, have invented certain new and useful Improvements in Valve-Spring Lifters, of which the following is a specification.

The present invention relates to a tool for facilitating the removal of puppet valves of the type commonly employed in internal combustion engines and certain types of steam engines.

More particularly, the invention comprises
15 a device for compressing and holding com-
pressed the valve spring, while the spring
retaining device is removed, to permit the
removal of the valve and its stem in the
usual well known manner. Various forms
20 of such devices are known to the art, and are
widely used. The object of the present in-
vention, however, is to provide a device of
the type described which is quick-acting,
and which holds the spring compressed, so
25 that the operator has both hands free to
remove the retaining device. A further ob-
ject is to provide for easy and quick adjust-
ment of the tool for valve springs of various
lengths. The device, moreover, is simple
30 and strong in construction, and cheap to
manufacture.

With these and other objects in view, the invention consists in the novel combination of parts hereinafter described, illustrated in the accompanying drawings, and pointed out in the claim hereto appended, it being understood that minor changes may be made in form and construction, within the scope of the claim, without departing from the spirit of the invention or sacrificing any of the advantages thereof.

In order to more fully comprehend the invention, reference should be had to the accompanying drawings, wherein:

45 Figure 1 is a side elevation of my valve spring lifter.

Fig. 2 is a plan view of the same.

Fig. 3 is a section taken in the direction of the arrows on the line 3—3 of Fig. 1.

50 In the drawings, the reference numeral 1, designates a bar, preferably square or rectangular in section, whose lower end is perpendicularly bent to form a transverse arm 2. Said transverse arm is forked at its end, 55 as at 3, to straddle the valve stem (not shown), and is cupped, as at 4, to provide

a seat for the lower end of the valve spring (also not shown), so that said forked end will not slip out from under the spring when pressure is applied thereto. The upper portion of the bar 1 is provided with a series of spaced transverse holes 5, disposed at right angles to the direction of the arm 2.

An upper transverse arm 6 is carried by a sleeve 7, the latter being slidably mounted upon the bar 1. Said upper arm, which is disposed parallel to the lower fixed arm 2, is bent downwardly at its outer end, as at 8, and is provided, at the extremity of said bent portion, with a centering point 9, adapted to bear against the valve head (not shown). 65 70

A lever 10, preferably formed of a flat strip of metal bent double and having its two members slightly spaced, is bent upwardly near one end, as at 11, and straddles the bar 1 at said upwardly bent end, the members of said lever being spread for this purpose, as shown at 12. A removable pin 13, preferably retained by a cotter-pin 14, pivotally connects the upwardly turned portion 11 of said lever 10 with the bar 1, said pin being adapted to be placed in any one of the holes 5 in said bar. A link 15 has one end pivotally connected with said lever at 16, at the bend therein, and the other end of said link is bifurcated, to straddle the upper arm 6, and is pivotally connected therewith at 17. 75 80 85

It will be readily seen that a movement 90 of the lever 10 from the position shown in dotted lines in Fig. 1 to that shown in full lines results in a downward movement of the upper arm 6 with respect to the lower arm 2, the sleeve 7 sliding upon the bar 1. 95 This movement is sufficient to compress the valve spring (not shown) the required distance to permit the removal or other operation of the retaining device (also not shown). It will also be seen that when the 100 lever is moved all the way down, the pivot 16 is carried beyond a line joining the pivots 13 and 17, so that no amount of upward force exerted upon the upper arm 6 can move the same. The tool therefore holds 105 the valve spring compressed without further attention on the part of the operator.

In using the device, the operator, using the upper portion of the bar 1 as a handle, places the forked end 3 of the lower arm 2 against the lower end of the valve spring (not shown) which is to be compressed, and

removing the pin 13 and raising the lever 10, allows the upper arm 6 to drop until its end 9 rests upon the head of the valve (not shown). He then places the pin 13 in 5 the lowest possible hole 5, and depresses the lever 10. This raises the bar 1 and the lower arm 2, compressing the spring the required amount and holding it in such position. The operator then has both hands free 10 for removing or otherwise operating the retaining device (not shown). The device is, therefore, readily adjustable and exceedingly easy to operate.

Having thus described my invention, what 15 I claim as new and desire to protect by Letters Patent is:—

A valve spring lifter comprising a bar provided with a plurality of transverse holes, a fixed arm extending laterally therefrom, 20 a movable arm slidably mounted upon said bar and disposed substantially paral-

lel to said fixed arm, an angle lever associated with said bar for raising and lowering said arm, a removable pin adapted to pivotally connect the end of the short arm of 25 said lever with said bar at any one of the holes therein, and a link connecting the angle of said lever and said movable arm, the pivotal point of connection of said link and arm adapted when said lever is in its 30 lowest position for lying below a line intersecting the pivotal connection between said lever and bar and link and arm, thereby locking the arm from upward movement by pressure applied thereto.

35 In testimony whereof I have signed by name to this specification in the presence of two subscribing witnesses.

POSEY W. BETTINGER.
